UNITED STATES PATENT OFFICE.

ERIK GOTTFRIED ÖSTERBERG, OF WORCESTER, MASSACHUSETTS.

SWIMMING DEVICE.

1,113,820.

Specification of Letters Patent. Patented Oct. 13, 1914.

Application filed November 25, 1913. Serial No. 802,929.

To all whom it may concern:

Be it known that I, ERIK GOTTFRIED ÖSTERBERG, a citizen of the United States, and a resident of Worcester, in the county 5 of Worcester and State of Massachusetts, have invented a new and Improved Swimming Device, of which the following is a full, clear, and exact description.

The object of the invention is to provide a 10 new and improved swimming device for use on a person's foot to facilitate swimming, to enable the swimmer to make better speed and to more effectively sustain the swimmer especially when playing water polo or other 15 aquatic games.

In order to accomplish the desired result use is made of a bracket attached to a shoe or a slipper and having a peak-shaped upper portion extending over the front end 20 of the shoe or slipper, a pair of wings hinged on the top of said bracket and limited in their downward swinging motion by the bracket, and limiting means for limiting the upward swinging motion of the wings. 25 Use is also made of a brace connected with the upper portion of the bracket and with an ankle band arranged for removable attachment to the ankle of the user of the device.

30 A practical embodiment of the invention is represented in the accompanying drawings forming a part of this specification, in which similar characters of reference indicate corresponding parts in all the views.

35 Figure 1 is a perspective view of the swimming device as applied and when in use while swimming; Fig. 2 is a front end elevation of the same with parts in section and showing the wings extended; and Fig. 3 is a 40 front elevation of the same with the wings folded.

In the general construction of the swimming device use is made of a shoe or slipper A adapted to be worn on the foot of the swimmer in the usual manner. On the forward end of the under side of the sole A' of the shoe or slipper A is secured an attaching plate B by screws, nails or other fastening devices, and the said attaching 45 plate is provided at its rear end with side-wise-extending lugs B' projecting beyond the side edges of the sole A'. To the rear portion of the attaching plate B and extending over the side lugs B' is secured the bottom C' of a bracket C having side members C² extending upwardly from the side of the

bottom C' and the side members C² terminate in upwardly and inwardly inclined top members C³ forming a bearing C⁴ at the top of the bracket, as plainly indicated in the drawings. In this bearing C⁴ is held a longitudinally-extending pintle D' on which a pair of wings D are mounted to swing up and down, the downward movement of the said wings D being limited by the upper ends of the side member C² of the bracket C, as plainly indicated in Fig. 3. The wings D are preferably slightly dished on the under side to offer more resistance to the water.

In order to limit the upward swinging movement of the wings D use is made of lugs E secured to the under side of each wing D and to which the ends of a piece of cord F are secured, the said cord passing around a cross plate C⁵ connecting the side members C² of the bracket C with each other, as plainly indicated in the drawings. The cross plate C⁵ reinforces the bracket C and is provided with downwardly extending retaining lugs C⁶ each extending around the cord F so as to hold the same against lateral shifting on the plate C⁵. The cords F allow the wings D to swing downward into tilted position and limit the upward 85 swinging motion of the said wings so that the latter assume a nearly horizontal position when extended as indicated in Figs. 1 and 2. The cross plate C⁵ is preferably arched and provided at the ends with depending flanges C⁷ adjustably clamped by bolts C⁸ extending through vertical slots C⁹ in the said side members C². On loosening the bolts C⁸ the cross plate C⁵ can be raised or lowered to fit more or less snugly 95 over the top of the shoe or slipper A.

In order to give more stability to the swimming device use is made of a flexible brace G connected with the upper end of the bracket immediately below the pintle 100 D', and this brace G is hooked onto a hook H' on an ankle band H passed around the ankle of the wearer's foot and secured thereto, as plainly shown in Fig. 1.

When the swimmer draws the foot toward 105 the body then the wings D move into closed or folded position by the resistance of the water against the outer face of the wings, and when the user moves the foot outward away from the body then the wings D are 110 caused to swing open by the pressure of the water against the under side of the

wings, so that the opened-up wings present a large sustaining surface and thereby assist the swimmer in moving forward.

From the foregoing it will be seen that 5 during swimming or treading water the wings D are alternately opened and folded according to the movement of the leg. Thus when the leg is drawn inward toward the body the wings D offer very little resistance, 10 but when the leg is moved outward the wings open and thus assist in propelling the person forward.

In practice, the bracket C as well as the 15 wings D are preferably made of aluminum to reduce the weight to a minimum, and by arranging the bracket C in the manner described the user of the swimming device can readily walk about without interference by the wings.

20 The swimming device shown and described is very simple and durable in construction, and as it forms a permanent part of the shoe or slipper A it can be readily donned or cast off according to the desires 25 of the user.

Having thus described my invention, I claim as new and desire to secure by Letters Patent:

1. A swimming device, comprising foot- 30 gear, a bracket attached to the forward end of the footgear and having a peak-shaped upper portion, wings hinged on the said upper portion of the bracket to swing into extended or folded position, the said bracket 35 forming a stop for the wings when in folded position, flexible stops for limiting the movement of the wings when moving into extended position, and means for flexibly connecting the upper end of the bracket with 40 the ankle of the wearer.

2. A swimming device, comprising a foot- gear, a bracket attached to the forward end of the footgear and having a peak-shaped upper portion and an adjustable plate connecting the side members of the bracket, 45 wings hinged on the said upper portion of the bracket to swing into extended or folded position, the said bracket forming a stop for the wings when in folded position, and 50 flexible stop members secured to the under side of the said wings and to adjustable plate of the said bracket to limit the movement of the wings when moving into extended position.

55 3. A swimming device, comprising a foot- gear, a bracket attached to the forward end of the footgear and having a peak-shaped upper portion, wings hinged on the said upper portion of the bracket to swing into

extended or folded position, the said bracket 60 forming a stop for the wings when in folded position, limiting stops for limiting the movement of the wings when moving into extended position, a brace extending longitudinally and connected at its forward end 65 with the said upper portion of the bracket, and an ankle band adapted to be attached to the wearer's ankle, the rear end of the said brace being attached to the said ankle 70 band.

4. A swimming device, comprising a shoe, an attaching plate secured to the sole of the shoe near the forward end thereof and bearing side arms projecting beyond the side edges of the sole, a bracket having a 75 bottom attached to the said attaching plate, the said bracket having side members rising from the said bottom and terminating in upwardly and inwardly inclined top members, a cross plate connecting the upper ends 80 of the side members with each other, the cross plate being integral, downwardly-extending retaining lugs, a longitudinally-extending pintle carried by the said top members, wings hinged on the said pintle 85 and adapted to swing up and down, the downward movement being limited by the said side members of the bracket, and cords held on the said lugs and connected with the under side of the said wings. 90

5. A swimming device, comprising a bracket adapted to be attached to the sole of a shoe and having a peaked upper end, wings pivoted to the upper peaked end of said bracket, cords secured to the wings and 95 bracket, and a flexible brace having one end secured to the upper end of the bracket and carrying at its other end a strap adapted to be secured around the ankle of the wearer.

6. A swimming device, comprising a 100 bracket adapted to be secured to the sole of a shoe and having a peaked upper end and an adjustable plate connecting the sides of the bracket, wings pivoted to the upper peaked end of the bracket, cords secured to 105 the under side of the wings and to the adjustable plate of the bracket, and a flexible brace having one end secured to the upper end of the bracket and carrying at its other end a strap adapted to be secured around the 110 ankle of the wearer.

In testimony whereof I have signed my name to this specification in the presence of two subscribing witnesses.

ERIK GOTTFRIED ÖSTERBERG.
